(57) **CLAIM**

The ornamental design for a cytometer display screen, as shown and described.

DESCRIPTION

FIG. 1 is a front view of a first embodiment of a cytometer display screen of our new design.

FIG. 2 is a front view of a second embodiment of a cytometer display screen of our new design.

FIG. 3 is a front view of a third embodiment of a cytometer display screen of our new design; and,

FIG. 4 is a front view of a fourth embodiment of a cytometer display screen of our new design.

The portions of the display screen, text, and other features depicted in broken lines are not part of the claimed design.
